UNITED STATES PATENT OFFICE

HARRY E. CROSBY, OF HUNTINGTON PARK, CALIFORNIA

DESIGN FOR A LIQUID-DISPENSING-MACHINE CASING

Application filed October 22, 1930. Serial No. 37,345. Term of patent 7 years.

To all whom it may concern:

Be it known that I, HARRY E. CROSBY, a citizen of the United States, residing at Huntington Park, in the county of Los Angeles and State of California, have invented a new, original, and ornamental Design for Liquid Dispensing Machine Casing, of which the following is a specification, reference being had to the accompanying drawing, forming part thereof.

Figure 1 is a front elevation, and Figure 2 is a top plan view of my new liquid dispensing machine casing.

The reverse elevational appearance of the dispenser is plain.

I claim:

The ornamental design for a liquid dispensing machine casing, as shown and described.

In testimony whereof I affix my signature.

HARRY E. CROSBY.
